UNITED STATES PATENT OFFICE.

EDMUND J. KANE, OF CHICAGO, ILLINOIS, ASSIGNOR TO INTERNATIONAL HARVESTER CORPORATION, A CORPORATION OF NEW JERSEY.

CARBURETER.

1,108,181.

Specification of Letters Patent. Patented Aug. 25, 1914.

Application filed June 30, 1913. Serial No. 776,623.

To all whom it may concern:

Be it known to my concern,
that I, EDMUND J. KANE, a
citizen of the United States, residing at Chi-
cago, in the county of Cook and State of
Illinois, have invented certain new and use-
ful Improvements in Carbureters, of which
the following is a full, clear, and exact speci-
fication.

This invention relates to carbureters for
internal combustion engines.

The object of this invention is to obtain the proper proportions of the ingredients of an explosive mixture for internal combustion engines operating on varying loads and speeds. This object is accomplished by providing a carbureter having an air passage-way with fuel and water inlets associated therewith, and means for localizing a vacuum, caused by the suction of an engine, around the fuel and water inlets in accordance with working conditions, to make the operation of the engine economical under all conditions.

The invention is illustrated on the accompanying sheet of drawings in which—

Figure 1 is a side elevation of my carbureter; Fig. 2 is a front elevation of the same carbureter; Fig. 3 is a plan view of the carbureter; Fig. 4 is a fragmentary detail sectional view of the carbureter, showing the throttling valve in different positions, the section of the valve being taken along the plane of line 4-4 of Fig. 5; and, Fig. 5 is a detail view of the throttling valve.

35 The various novel features of my invention will be apparent from the description and drawings, and will be particularly pointed out in the appended claims.

40 One of the main problems in dealing with carbureters is to obtain the proper proportion of the ingredients of the combustible mixture at different engine loads and speeds. It is a well known fact that with an oil or fuel nozzle in an air passageway, the relative proportions of air and oil will vary with the different speeds of the air through the passageway. That is, if at a low air speed, there is obtained a mixture, for instance of 15 parts of air to one of oil, at a higher air speed the mixture will contain relatively more fuel; for example, ten parts of air to one of oil. If the nozzle is adjusted so that the best mixture is obtained at low air speeds, it will be too rich at higher air speeds. If the nozzle is adjusted at higher

45

50

55

speeds, the mixture will be too lean at low air speeds. The air speed in the inlet pipe of an engine depends upon the load and speed of the engine. When attempting to burn the heavier fuels, such as kerosene and distillate, water must be introduced into the mixture in an entirely different proportion to the amount of oil. It has been found by experiment, for no loads and light loads up to a certain point no water is required. In fact water would be detrimental. Beyond this point water is introduced, the heavier the load the greater the amount of water. This carbureter is designed to keep the air at the proper velocity at all loads, and to control automatically the inhalation of water so that at no load and light load water will not be drawn into the mixture, while at heavy loads it will be. The carbureter includes a main body portion 10, having an air passageway 11, the section of which (see Fig. 3) is somewhat irregular in that one end of the section is large when compared with the other end. The section of the air passageway might be said to be pear-shaped. This main body portion 10 is also provided with a cylindrical portion 12, in which is adapted to operate a throttling valve 13 which is automatically operated by the engine governor (not shown), the connection to which is indicated by a rod 14. Secured to the top of the main body portion 10 is a cover member 15, having a passageway 16 communicating with the air passageway 11. Secured to the side of the main body portion 10 of the carbureter is a receptacle 17 divided by a central partition 18 to form an oil chamber 19 and water chamber 20. The oil chamber is provided with a partition 19^a for controlling the oil level, the oil passing into the chamber through an inlet pipe 21 and overflowing into an outlet pipe 22. The water receptacle has a similar partition 23 and inlet and overflow pipes 24 and 25 respectively. A nozzle 26 leading from the oil chamber projects into the larger side of the air passageway 11 above the throttling valve 13. The nozzle is provided with a hand-operated needle valve 27 for regulating the flow therefrom. A similar nozzle 28 connected with the water chamber projects into the smaller side of the air passageway 11 above throttling valve 13. This nozzle is also provided with a manually controlled needle valve 29. The throttling 105

valve is provided with a radial portion 30 which prevents passage of air through its side of the throttling valve. This throttling valve also has a winged portion 31 in which 5 there is a cavity or depressed portion 32 which receives the water nozzle 28 to permit said throttling valve to be moved into closed position.

In the operation of internal combustion engines, it is necessary that the explosive mixture be comparatively rich under no load and light load conditions, due to the fact that the compression is low. The richness of the mixture may be diminished gradually as 10 the load increases by drawing in a relatively greater amount of air. When the engine reaches a certain per cent. of its rated horsepower and is running on kerosene or other heavy fuels, it is necessary that water be 15 added to the mixture, not only for the cooling effect it may have, but also to assist in diminishing the richness of the mixture and to prevent pre-ignition of the explosive mixture, which is the cause of pounding in the 20 cylinder. If water were permitted to form a part of the mixture when the engine is working below this certain per cent. of its rated horsepower, such water would prove to be detrimental. When the engine is running 25 at no load, or light loads, the throttle valve 13 is nearly closed; that is, the air passageway 11 is closed at all points with the exception of a small opening adjacent the liquid fuel or oil inlet nozzle 26. It will be 30 apparent that when there is only a slight opening at the oil nozzle, the smaller portion of the air passageway 11 adjacent the water inlet nozzle will be closed, due to the diminishing dimensions of the cross section of the 35 air passageway 11 from the oil nozzle to the water nozzle, as shown particularly in Fig. 3. It will be observed also that the dotted line position of the throttling valve in Fig. 1 is the same as the full line position of the 40 throttling valve in Fig. 4. From this it will be seen, that due to the particular section of the air passageway 11 there is a small opening between the winged portion 31 and an internal edge 33 of the carburetor body formed 45 by the intersection of the air passageway 11 and cylindrical portion 12, permitting a flow of air past the oil nozzle 26, and that the opposite end of the throttling valve adjacent the depressed portion thereof overlaps the edge 33 of the carburetor body preventing a flow of air past the water inlet nozzle. It is seen, therefore, that in this 50 position of the throttling valve, which corresponds to no load, the vacuum formed in the cylinder of the engine extends to the lower part of the carburetor body and also beyond the opening of the throttling valve. The distance the vacuum extends beyond depends upon the size of the opening with the 55 throttling valve in the position shown in

dotted lines in Fig. 1, and in the full lines in Fig. 4. In this position, the vacuum is limited or localized around the oil nozzle to the exclusion of the water nozzle. The resultant rush of air past the oil inlet nozzle 26 draws fuel from said nozzle, the two mixing and passing into the combustion chamber of an internal combustion engine where the mixture is ignited and expanded for doing work. As the load on the engine increases or when the engine is running below normal speed, the throttle valve gradually opens farther, admitting more air. By the same action the area of the opening is enlarged so that the rush of air past the nozzle and the vacuum produced are practically constant. When the engine reaches a certain per cent. of its rated horse-power, the throttle valve will have reached the dotted line position in Fig. 4 or to the position 70 where there will be a slight opening past the water inlet nozzle 28. With the throttling valve in this position, the vacuum which has heretofore been localized only around the oil inlet nozzle, is now permitted to reach the space surrounding the water inlet nozzle 75 whereupon a limited amount of water will be drawn into the mixture on its way to the combustion chamber of the cylinder. With a further increase of load the throttling valve 13 continues to rotate in a clockwise direction as viewed in Figs. 1 and 4, permitting a greater flow of air, oil and water to 80 meet the requirements of heavy load conditions. In a similar manner, when the load 85 on the engine decreases from full load, the effective area of the air passageway 11 is gradually diminished, the water inlet nozzle being cut out of the vacuum zone when the load on the engine has decreased below this 90 certain per cent. of its rated horse-power, the vacuum being again localized around the oil inlet nozzle 26. It is seen that the construction of this carburetor is such that the 95 throttle valve acts not only as a throttle but also as an adjustable choker so that when the throttle is closed, by the action of the 100 governor, the speed of the air past the fuel nozzle is increased, and the proper amount of fuel taken in. The relative amount of 105 fuel in the mixture can be varied by changing the position of the oil nozzle with respect to the edge of the throttle valve. If at full 110 loads the proper mixture of air, fuel, and water is obtained, and at light load too 115 much water is in the mixture, the amount of water can be controlled by making the distance between the nozzles greater, or by making the area of the fuel nozzle end greater in proportion to the area of the water nozzle end, so that the vacuum at light 120 loads is concentrated to a greater extent around the oil nozzle or does not extend to the water nozzle so quickly. In my carburetor it is possible to localize the vacuum 125 130

around the oil nozzle alone to meet certain load conditions and also around the oil and water nozzles to meet other load conditions.

It is evident that various modifications can be made in the particular arrangement of my invention herein shown and described, and it is my intention to cover all such modifications which do not involve a departure from the spirit and scope of my invention.

10 What I claim as new is:

1. A carbureter for internal combustion engines, said carbureter having an air passageway, liquid fuel and water inlets directly associated with said air passageway, and means for localizing engine vacuum around the fuel inlet to the exclusion of the water inlet.

2. A carbureter for internal combustion engines, said carbureter having an air passageway, fuel and water inlets directly associated with said air passageway, and means for localizing engine vacuum around one of said inlets to the exclusion of the other.

25 3. A carbureter for internal combustion engines, said carbureter having an air passageway, fuel and water inlets directly associated with said passageway, and means for first localizing engine vacuum around the fuel inlet and then around the fuel and water inlets as the load on the engine increases.

35 4. A carbureter for internal combustion engines, said carbureter having an air passageway, fuel and water inlets directly associated with said passageway, and means for localizing successively a vacuum around the fuel and water inlets as the engine load increases.

40 5. A carbureter for internal combustion engines, said carbureter having an air passageway of irregular section, fuel and water inlets associated with different parts of said passageway, and a throttling valve in said passageway by means of which a vacuum may be localized around one of said inlets to the exclusion of another.

45 6. A carbureter for internal combustion engines, said carbureter having an air passageway of irregular section, fuel and wa-

ter inlets associated with different parts of said passageway, and a throttling valve in said passageway by means of which a vacuum may be localized successively around said inlets.

55

7. A carbureter for internal combustion engines, said carbureter having an air passageway with relatively large and small portions, a fuel supply nozzle associated with the large portion of said air passageway, a water supply nozzle associated with the small portion of said passageway, and a throttling valve located in said passageway by means of which localization of a vacuum may be controlled around said nozzles to vary the richness of an explosive mixture.

8. A carbureter for internal combustion engines, said carbureter having an air passageway with relatively large and small portions, a fuel inlet nozzle associated with the large portion of said passageway, a water inlet nozzle associated with the small portion of said passageway, an automatically actuated valve for opening and closing said air passageway in a manner to localize a vacuum in the large portion of said air passageway around said fuel nozzle and then around both the fuel and water nozzles as the engine load varies.

9. In a carbureter for internal combustion engines, a member having an air passageway extending therethrough with large and small portions, said member having a cylindrical portion extending transversely therethrough forming an interior edge, fuel and water inlet nozzles associated respectively with the large and small portions of said air passageway, and a throttling valve located in the transverse cylindrical portion the edge of which valve is at an angle with respect to said interior edge to control a flow of air past said fuel and water inlet nozzles in accordance with operating conditions.

In testimony whereof I affix my signature, in the presence of two witnesses.
